FIG. 1

FIG. 2

FIG. 3

FIG. 4

FIG. 5

FIG. 1 is a front side elevation view of a casing for an apparatus for mixing fluids in a test tube or similar container with broken lines indicating an alternative position of the controls and the positioning of the receptacle to hold the fluid-filled container during the mixing period;

FIG. 2 is an end elevation view thereof;

FIG. 3 is a rear elevation view thereof;

FIG. 4 is a top plan view thereof; and

FIG. 5 is a bottom plan view thereof.

The dominant features of my design are shown in solid lines in the drawings.

I claim:

The ornamental design for a casing for an apparatus for mixing fluids in a test tube or similar container, as shown and described.
